UNITED STATES PATENT OFFICE

LEE B. GREEN, OF LAKewood, OHIO, ASSIGNOR TO THE GLOBE MACHINE & STAMPING COMPANY, OF CLEVELAND, OHIO, A CORPORATION OF OHIO

GRILLE OR SCREEN FOR AUTOMOBILE RADIATORS

Application filed January 5, 1931. Serial No. 506,550.

My invention relates to grilles or screens for use in front of the radiator enclosure of an automobile to prevent loose leaves, twigs or the like from being tossed or drawn into the cells of the radiator core, and incidentally also to add to the ornamental appearance of the car.

In the employing of wire screens, grilles or other foraminous guard members in front of automobile radiators for this purpose, it heretofore has usually been customary to attach such a guard member by bolts or screws either to the radiator core or to a frontal portion of the radiator shell or other radiator-core enclosure. This practice has the serious objections of requiring drilling, tapping or other mechanical operations; of leaving unsightly holes in the radiator front when the grille or other guard is detached; and of interfering with convenient access to the radiator core from the front of latter in case any of the cells of the core should still become clogged. Moreover, if the edge binding of such of screen or other guard is clamped tightly against a radiator front, dirt and other solid particles which have passed through the screen are apt to lodge between the radiator front and the parts of the screen adjacent to this binding, thereby producing an unsightly appearance and gradually interfering with the flow of air through the radiator core.

In some of its major objects, my invention aims to provide an arrangement whereby such a grille, screen or other guard can speedily and conveniently be supported in the desired guarding relation to a radiator front without requiring any drilling, tapping or other mechanical operations on any part of the automobile; whereby the attached guard will be freely spaced forwardly from the radiator front, so that any solid particles which pass through its perforations can readily drop out; and whereby the entire guard assembly can easily be removed without leaving any exposed holes or other unsightly marring of the radiator front.

In a further object, my invention aims to provide means whereby such a grille, screen or other guard can readily be attached to and

supported entirely by the cross-bar which extends in front of the radiator on many modern types of automobiles; such cross-bars being commonly provided both for connecting the front fenders to add rigidity to these fenders, and for supporting the head lamps of the automobile. For such a supporting of the grille or other guard from a frontal cross-bar, my invention aims to provide guard-supporting means which can easily be adjusted laterally longitudinally and vertically with respect to the cross-bar, and also rotationally in the general plane of the guard, so that this guard can readily be centered with respect to the adjacent frontal portion of the radiator enclosure.

Moreover, my invention aims to provide simple means for uniformly spacing such a guard from the adjacent frontal portion of a radiator shell or other radiator-core enclosure without employing any fastening elements attached to this enclosure, and aims to provide an arrangement whereby these spacer means will also prevent the guard from rotating about the axis of the supporting cross-bar.

More particularly, my invention aims to provide spacer means and supporting means as well as spacers all connected to such a grille, screen or other guard as to constitute an assembly which can speedily be attached as a unit to the supporting cross-bar and adjusted so that the spacer means will bear against the radiator front of the car with such a pressure to prevent rattling, although sufficiently yielding to compensate for slight irregularities in the spacings of adjacent parts. So also, my invention aims to provide means for detachably supporting the spacers from the grille or other guard, so that these spacer means can readily be replaced if necessary, and aims to dispose the spacers so that the pressure on them will not distort the guard.

Still further and also more detailed objects will appear from the following specification and from the accompanying drawings, in which

an automobile equipped with a grille or screen embodying my invention.

Fig. 2 is a fragmentary plan view of the same.

5 Fig. 3 is a fragmentary and enlarged vertical section taken along the line 3-3 of Fig. 2.

Fig. 4 is a vertical section taken along the zigzag line 4-4 of Fig. 3.

10 Fig. 5 is a horizontal section taken along the line 5-5 of Fig. 3.

Fig. 6 is rear elevation of one of the spacer-carrying brackets and the adjacent portion of the binding of the grille or screen, drawn 15 on a larger scale than Fig. 5.

Fig. 7 is a vertical section, taken along the line 7-7 of Fig. 6.

Fig. 8 is a perspective view of one of the spacer-carrying brackets.

20 Fig. 9 is a reduced rear elevation of the binding of the grille or screen, together with the spacer-carrying brackets and spacers attached to this grille or screen.

25 In the drawings, the illustrated portion of an automobile includes a horizontal cross-bar 1 connecting the two front fenders 2 and supporting the head lamps 3, which cross-bar is spaced forwardly from the front of the radiator shell 4 and extends approximately at the level of the midheight of the 30 radiator shell.

The attached grille or guard member comprises a wire screen 5 which has its peripheral portion bordered by a binding 6, this binding being shown (Fig. 5) as of a channel-sectioned type having the inwardly directed edge portions of each channel web recurved to form wings 6A which bear against opposed face portions of the screen 40 after the manner more fully disclosed in my copending application Serial No. 543,148, filed June 9, 1931 on a metal screen or grille binding. These opposed recurved wings 6A are spread sufficiently apart at selected portions of the frame-like bindings, and preferably adjacent to the corners of this binding when the latter forms a substantially polygonal frame, so as to have one shank 7A of a U-sectional spacer-supporting bracket 45 clamped between the wire screen 5 and the rearward one of the two recurved webs 6A of the binding, this bracket shank being brazed to the latter web.

50 The other shank 7B of the spacer bracket (pictured separately in Fig. 8) has a perforation 8 through which a diametrically contracted forward portion of a spacer member extends. This spacer member is desirably of elastic rubber and has near its rear end a peripheral groove 10, the bottom of which groove corresponds approximately in vertical section to the bore of the bracket perforation 8. After the spacer member is attached to the bracket (by compressing the 55 portion 9A forward of this groove so as to

snap this head-forming portion through the perforation 8) the rear wall of the said groove in the rubber spacer affords an annular shoulder bearing against the rear shank 7B of the bracket, and the forward groove wall 70 latches the spacer to the said bracket shank, leaving the main portion 9B of the spacer extending rearwardly from the bracket.

The number of bracket-supported spacers thus mounted on the grille or other guard member may be varied, but with the rigidity afforded to the binding by its above described sectional formation, it is usually sufficient to provide two such spacers at each side of the frame or binding, and these are preferably mounted adjacent to the upper and lower corners of the frame.

Welded to the outer edge of each riser member of the binding adjacent to the level of the cross-bar 1 is a wing 10 (Fig. 3) which extends rearwardly toward the front face 11 of the radiator enclosure, and wing which has two vertically spaced perforations for receiving bolts 12. Each of these bolts extends through a vertical slot 13 in a bracket 90 14 which has an arm 14A extending forwardly at right angles to the face of the grille and beyond the cross-arm 1. This arm has a horizontal slot 15 for receiving a bolt 16 which extends parallel to the said grille 95 face and the cross-arm through the perforation in an upright wing 17 on a U-shaped clamp 18 which straddles the cross-arm 1 and is secured to the latter by a bolt 19. In practice, the wings 10 are preferably secured to the opposite side portions of the grille binding at such heights that the bracket arm 14A will extend above the cross-arm 1 when the grille is in the desired position with respect to the radiator front, thereby permitting the 100 clamps 18 to be slid down over the cross-arm to support the grille before the bolts 19 are attached and before the bolts 12 and 16 are tightened.

Thus arranged, each bracket 14 together with the adjacent cross-arm gripping clamp 18 with its wing 17 constitutes an attaching member for adjustably supporting the grille from the cross-arm. These two attaching members, together with the spacer-supporting 115 brackets 7 and the spacers mounted on those brackets are attached to the grille before securing the resulting assemblage to the automobile. To attach it, the grille is slid downward between the cross-bar 1 and the radiator front portion 11, with the bolts 16 somewhat loosened and the clamp bolts 19 detached, so as to permit the forked clamps 18 to straddle and seat on the cross-bar. These clamps can then be slid sideways on the cross-bar to center the grille laterally with respect to the radiator front, and the vertical slots 13 allow the grille to be raised or lowered with respect to the said clamp to center the grille with respect to the 120 radiator front. When the grille has thus 130

been centered, the bolts 12 and 19 are tightened, after which the frame of the grille is pressed rearwardly to a firm engagement of the spacers 9B with the radiator front, the 5 needed horizontal movement being permitted by the slots 15, and the bolts 16 are tightened to maintain this engagement.

When thus attached, the grille assembly is supported entirely by the cross-arm, and the 10 engagement of the upper and lower spacers with the radiator front prevents this assembly from rocking about the axis of the cross-arm, while the compressibility of the rubber spacers allows these to compensate for any slight 15 deviations in the spacing between different portions of the grille frame and the radiator front. The U-shaped form of the spacer-supporting brackets may allow a further slight yielding for the same purpose, so that the 20 grille—although supported only by two clamps and not attached in any manner to the radiator core or the radiator front—is firmly supported and will neither rattle nor shift when the car is in motion.

25 By thus spacing the entire grille, including its binding, forwardly from the radiator front and by employing compressible material (such as rubber) for the spacers, I entirely avoid a scratching of either the radiator front 30 or the grille, and also prevent dust from lodging between the grille and radiator front. If the spacers wear or shrink in time, the bracket slots 15 readily permit the user to make the needed adjustments; and when the 35 spacers harden or otherwise need replacing, new ones can readily be substituted.

During the attaching, the grille-attaching means permit adjustments both longitudinally, vertically and transversely of the car; 40 and the providing of vertical slots 13 in each of the two attaching means also permits a separate vertical adjustment for each side of the grille to effect a rotation of the grille in its own plane substantially about the middle 45 of the grille. Consequently, the user can readily dispose the grille so that it accurately conforms to the shape of the adjacent radiator front part of the car for which the grille was formed, thereby adding also to the appearance 50 of the car. And, since the parts permanently secured to the grille—namely the spacer-supporting brackets 7 and the wings 10—can readily be attached to grille bindings of widely varying frame shapes, my invention readily 55 lends itself for use with radiator fronts of different sizes and forms.

However, while I have heretofore described my invention in an embodiment including numerous desirable details of construction 60 and arrangement, I do not wish to be limited in these respects, since many changes might obviously be made without departing either from the spirit of my invention or from the appended claims. Nor do I wish to be limited 65 to the use of my invention in connection with

automobiles, since it might be employed with equal advantage for supporting grilles or the like for other purposes.

I claim as my invention:

1. An attachment to a vehicle having a 70 horizontal cross-bar spaced forwardly from and extending parallel to a frontal vehicle portion, comprising: a grille or the like comprising a foraminous main portion and a binding framing the said main portion, the 75 said grille extending between the cross-bar and the said frontal vehicle portion; two webs fast upon and extending rearwardly from opposite side portions of the binding, bumper means extending rearwardly from 80 spaced portions of the binding and pressing against but unsecured to the said frontal vehicle portion, and two connecting means respectively securing the two webs to the said cross-bar for supporting the grille with 85 the bumper means in their said disposition, the said connecting means being arranged to permit both a horizontal and a relatively 90 independent vertical adjustment of the grille with respect to the cross-bar.

2. A vehicle attachment as per claim 1, in which each of the connecting means comprises a clamp gripping the cross-bar, and two connecting members respectively fastened to the said clamp and to one of the 95 said webs, the member fastened to the web being vertically adjustable with respect to the web.

3. A vehicle attachment as per claim 1, in which each of the connecting means comprises a clamp gripping the cross-bar and having an ear provided with a perforation, a web secured to the grille frame and provided with two vertically spaced perforations, a connecting member having a horizontal slot extending across the perforation in the clamp ear and having two vertical slots extending respectively across the two spaced perforations in the web, and three 105 bolts each extending through one of the said 110 perforations and the slot crossing that perforation.

4. The combination with a radiator front and a cross-bar extending parallel to and forwardly of the said front, of a grille disposed parallel to the said front between the said front and cross-bar, the grille comprising a foraminous member and a frame housing the peripheral portion of the foraminous member; spacer supports adjacent to spaced 115 portions of the frame and each having a foot clamped between the grille and a part of the said frame, spacer members each mounted on one of the spacer supports and extending rearwardly into the engagement with the 120 radiator front, and means interposed between the cross-bar and the grille frame for supporting the grille and pressing the said spaced members against the radiator front.

5. A grille or the like for use in front of 130

an automobile radiator, comprising a foraminous member, a frame housing the peripheral portion of the said member, spacer supporting brackets adjacent to spaced portions of the frame, and bumpers each mounted upon and extending rearwardly from one of the said brackets, each of the brackets being formed separately from the frame and having a portion thereof clamped between the frame and the foraminous member.

6. A grille or the like as per claim 5, in which each bracket is of a U-shaped section in a plane at right angles to the general plane of the frame and presenting the shanks of 15 its U-formation parallel to the said frame and behind one another, the forward shank of the bracket being clamped between the frame and the foraminous member and the rearward shank being formed for detachably 20 supporting one of the bumpers.

7. The combination with an upright grille comprising a foraminous member and a frame housing the peripheral portion of the said member, and a horizontal cross-bar extending forwardly of and parallel to the grille, of two adjustable means for supporting the grille from the said bar; each of the 25 said means comprising a web secured to one side of the grille frame and extending rearwardly beyond the said frame, a clamp fastened to the cross-bar and including a riser portion, a bracket extending alongside the web and the riser portion of the clamp, a single bolt connecting the bracket with the 30 riser portion of the clamp, and two bolts connecting the bracket with the web and having their axes rearward of the grille frame; the bracket having a horizontal slot through 35 which the said single bolt extends, and having two superposed vertical slots through 40 which the said two bolts respectively extend.

Signed at Cleveland, Ohio, December 31st, 1930.
